UNITED STATES PATENT OFFICE.

JOHN F. OHMER, OF DAYTON, OHIO, ASSIGNOR TO OHMER FARE REGISTER COMPANY, OF ROCHESTER, NEW YORK.

MEANS FOR ELECTRICALLY OPERATING THE OPERATING MECHANISM OF A FARE-REGISTER.

No. 911,519.

Specification of Letters Patent.

Patented Feb. 2, 1909.

Application filed October 3, 1907. Serial No. 395,680.

To all whom it may concern:

Be it known that I, JOHN F. OHMER, citizen of the United States, residing at Dayton, in the county of Montgomery and State of Ohio, have invented certain new and useful Improvements in Means for Electrically Operating the Operating Mechanism of a Fare-Register; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to electrical means for operating the counters and indicators of fare registers from various points of a car or other place where the registering machines are located.

The main actuating device of the registering machine is actuated by closing the electrical circuit through means of a single flexible connection extending on the interior of the car from a single circuit closer. The type of registering machine and the actuating mechanism thereof with which it is designed to use this electrical appliance, are illustrated in many of my former patents, principally among which might be mentioned Patents Nos. 694,322 of Feb. 25, 1902, and 718,867 of Jan. 7, 1903.

The present invention comprises certain improvements of the electrical actuating mechanism shown and described in my pending application Serial No. 378,734, filed June 13, 1907.

Preceding a detail description of the invention, similar reference characters indicate corresponding parts of the various views of the drawings hereto annexed which are as follows:

Figure 1, is a front elevation of a fare register or machine such as I have heretofore indicated with my improved electrical actuator shown in operative relation therewith. Fig. 2, is a view of the interior of a car showing the installation of a fare registering machine, the fare-selective and indicating devices and the electrical actuator in coöperative relation. Fig. 3, is a detail of the electro-magnet and immediate connections, together with the circuit closure

with a slight modification as compared with the electrical devices shown in Fig. 1, such modification comprising a flexible connection extending from the flexible connection which joins the circuit closure. Fig. 4, is a front elevation of the operating mechanism. Fig. 5, is a front elevation of the lower portion of the machine showing the counters. Fig. 6, is a side sectional elevation showing the connections between the operating mechanism and the counter mechanism.

The registering mechanism inclosed within the casing 1 comprises a series of detail fare counters 2, the corresponding fare indicators 3, the individual actuating members 2^a and the trip or passenger indicator wheels 4 with their interconnecting mechanisms, the main actuating member 5, the shiftable actuator 5^a and the bell crank lever 16, all of which features are common to the registering machines of my former patents as hereinbefore indicated. The indicating dials 6 arranged exterior to the register mechanism, together with the other fare-selective devices comprising the pointer 7 fixed to the setting rod 8 and the flexible connections 19 extending from said setting rod to the shiftable actuator 5^a at the rear of the registering machine, are also features of my former patents and need not be gone into in detail in connection with the present improvements.

The present invention comprises an electrical actuator through which the bell crank lever 6 may be actuated to lift the main operating member 5 through which the registering mechanism of the machine is actuated. This electrical actuator comprises a magnet 9 located at a suitable point exterior to the registering mechanism and in proximity to the actuating lever 6. This electro-magnet is energized by means of a suitable electric circuit comprising negative and positive conductors 10 which extend from the source of electrical supply through binding posts 11, said conductors 10 connecting with the opposite ends of the magnet winding in the usual manner through contact devices consisting of a circuit closure comprising two members 12 and 13. The electro-magnet has a movable core 14 which is properly connected to the bell crank lever 6 by means of a metallic rod or wire 15. When the magnet is energized by bringing

the members of the circuit closure together, the core 14 is magnetically drawn within the magnet and thus imparts a requisite movement to actuate the bell crank lever 6 to 5 actuate the main operating device 5 of the registering machine.

It will be understood that prior to each operation of closing the circuit, the desired fare to be registered is selected in the usual 10 manner by turning the setting rod 8 to a position to bring the pointer 7 to the proper indication on the dials 16. The circuit-closing member 13 is pivoted at 17 and is engaged at one end by a retaining lever 18 15 which maintains it in a normal or operative position through the instrumentality of a spring 20 which is connected to one end of said lever. Extending from the circuit-closing member 12 is a flexible connection 21 20 which passes over a suitable guide pulley 22 and extends in the form of a rope or cord 23 which runs through the car at suitable points within convenient grasp of the conductor. The necessary draft is applied to 25 this rope or cord to actuate the circuit-closing member 12 to engage the other member 13 to close the circuit. On one side of either of the circuit-closing members 12 or 13 is placed a suitable piece of insulating mate- 30 rial 24 in order that the circuit shall be broken after suitable contact has been made between the two circuit-closing members, and when said members are returning to their normal positions under the action of 35 the springs 20.

In order that there may be no uncertainty in the operations of the machine in registering and indicating the fares I connect the operating lever 6 to the flexible member 23 40 through which the circuit-closing member 12 is connected by a flexible connection 21; the flexible connection 25 which joins said lever 6, and the flexible connection 21 which joins the main flexible connection 23 pass over 45 suitable guide pulleys 22. By means of this connection 25 with the operating lever 6 the flexible member 23 is drawn taut or to the normal position by the register actuating mechanism assuming its normal position 50 after each operation of the machine. By this means the conductor or operator is able to determine definitely that a complete operation has been performed, when the flexible connection 23 has been drawn upon to close the 55 circuit. The flexible connection 25, in other words, is a means for signaling to the operator when the registration is completed, the flexible connection 23 in such cases being drawn taut; such means is a safeguard 60 against the improper or incomplete operations which might be due to an imperfect operation of the circuit closer, in which case, the flexible connection 23 would remain slack owing to the fact that the main operating member 5 has not been completely 65

moved to a position to actuate to their full extent, the register mechanism. This of course, would be due to the magnet-core 14 failing to receive a sufficient movement to actuate the lever 16 to the necessary extent. 70 The electrical devices are inclosed in a suitable box or casing 27 upon which the binding posts 11 are secured through which the conductors are directed to the terminals of the magnet winding and the circuit closer. It 75 will thus be seen that the electrical mechanism may be conveniently employed to operate any registering machine having as an element a lever or bar arranged to actuate the main operating mechanism of such a registering machine, and to place it in operative connection with such a machine, it is only necessary to screw the cabinet or mount it in position in suitable proximity to the machine and make the necessary connection between 80 the magnet and the operating mechanism, and run the flexible connection from the circuit closer to distant points. No change whatever is necessary in the construction of the register mechanism proper or the actuating mechanism 85 through which the register mechanism is directly operated. The magnet-core 14 is provided with a suitable air cushion within the magnet to reduce the force of the movement thereof when the magnet is energized. 90

So far as I am aware, I am the first to employ a stationary electro-magnet with direct connection between said magnet and the operating member through which movement is imparted to the registering and indicating 100 mechanism of a registering machine, such magnet being within a circuit controlled by a circuit-closer, which in turn, is controlled by a single flexible connection extending on the interior of a car. I therefore, do not 105 wish to limit myself to any particular form of circuit-closer and connections, but desire to claim broadly a stationary electro-magnet having a direct connection with a device or devices through which movement is imparted directly from the electro-magnet to the registering mechanism of the machine. 110

Having described my invention, I claim:

1. In a fare register, the combination with 115 register-actuating mechanism, of an electro-magnet connected with said actuating mechanism, an electric circuit for energizing said magnet, a circuit closer connected with one terminal of said circuit, a flexible connection extending to said circuit closer and by means 120 of which said circuit closer is actuated to close the circuit and to thus energize the magnet to impart movement to the register actuating mechanism.

2. In a fare register, the combination with 125 register-actuating mechanism, of an electro-magnet, a connection between the core of said magnet and the register-actuating mechanism, an electric circuit including said electro-magnet, a circuit closer for said circuit, a flexi- 130

ble connection extending to one member of said circuit closer and whereby said circuit closing member is actuated to close the circuit and thus energize the magnet, and a 5 flexible connection extending between the flexible connection of the circuit closer and the actuating mechanism of the register and whereby means are provided for enabling the operator to determine the complete operation of the actuating mechanism from the 10 energized magnet.

3. In combination with register mechanism, an electric power circuit comprising an electro-magnet, a switch controlling said circuit, a main line flexible connection to the switch, a branch flexible connection from the main line to the register mechanism and by which said flexible connections the switch is moved to complete the electric circuit and 20 to draw the main line flexible connection to normal position after each complete operation of the register mechanism.

4. In combination with the main actuating mechanism of a fare register, an electric 25 circuit, an electro-magnet within said circuit, a circuit closer controlling the current through the magnet, a main flexible connection with one member of the circuit closer, and by which the circuit closer is actuated 30 to close the circuit, a flexible connection between said main flexible connection and the actuating mechanism of the register, and a connection between the electro-magnet and said main actuating mechanism of said register. 35

5. The combination with the main actuating mechanism of a fare register, an electric circuit, an electro-magnet in said circuit, a connection between the core of said magnet 40 and the actuating mechanism of the register, a circuit closer comprising two members one of which is electrically connected with one terminal of the magnet winding and the other of which is connected with one terminal of the circuit, and a flexible connection 45 extending from one member of said circuit closer for actuating the same to close the circuit.

6. The combination with the main actuating mechanism of a fare register, means for 50 selecting a fare to be registered prior to the operation of said main actuating mechanism, an electric circuit and an electro-magnet energized by said circuit, a connection between the electro-magnet and the main actuating mechanism of the register whereby 55 said main actuating mechanism is operated to register the fare selected when the electro-magnet is energized, a circuit closer for said circuit, and means for actuating the circuit closer. 60

7. In combination with the main actuating mechanism of a fare register, an electro-magnet connected with said main actuating

mechanism, an electric circuit for energizing 65 said electro-magnet to actuate the main actuating mechanism of the register, a circuit closer comprising two members, a connection extending from one of said members whereby the circuit closer is controlled, and insulation interposed between the adjacent ends of the two members of the circuit closer for breaking the circuit when the two members of the circuit closer assume their normal position. 70

8. In a fare register, a plurality of fare counters, a shiftable actuator adapted to be moved to a position to operate a selected counter, means for so moving said shiftable actuator, a main operating mechanism for 80 operating the shiftable actuator to register the fares on a selected counter, an electric circuit, an electro-magnet in said circuit, a connection between said electro-magnet and the main operating mechanism whereby the 85 latter is actuated when the electro-magnet is energized, and a circuit closer controlling the current of the circuit. 75

9. In a fare register, a series of fare counters, a shiftable actuator adapted to be moved to positions to operate any one of said fare counters, means for determining the movement of said actuator, a main operating device adapted to operate said actuator when the latter is moved to the desired position 90 relatively to the counter to be operated, an electric circuit, an electro-magnet arranged between the terminals of said circuit, a circuit closer, and means extending from said circuit closer for operating the same to close the circuit and thereby energize the magnet, and a connection between said electro-magnet and the main operating mechanism and through which movement is imparted to the latter when the electro-magnet is energized. 100

10. In a fare register, a series of fare counters, actuating mechanism therefor, an electro-magnet, a connection between the core of said magnet and the main actuating mechanism, an electric circuit in which said magnet is arranged, a circuit closer, said electro-magnet and said circuit closer being arranged within an inclosing case, and a flexible connection extending from said circuit closer on the interior of a car and whereby said circuit closer is actuated to close the circuit and to thus energize the electro-magnet, and whereby the main operating mechanism of the register is actuated. 110

11. The combination with a plurality of 120 registering counters, and operating mechanism therefor, of an electric circuit, a magnet common to all of said counters and within said circuit, connections between said magnet and said operating mechanism, and a circuit closer to close and open the circuit to energize the magnet and thereby actuate the operating mechanism. 125

12. In a fare register, the combination with a plurality of registering counters, and actuating mechanism therefor, of an electric circuit, an electro-magnet connected with 5 said circuit, a circuit closer, a flexible connection leading to said circuit closer and by means of which it is closed to complete the circuit and to thereby energize the electro-magnet to impart movement to said actuating mechanism.

13. In a register mechanism, the combination with a plurality of registering counters and an actuating mechanism common to all 10 of said counters, of an electric circuit, an 15 electro-magnet in said circuit, a circuit closer to close and open said circuit to energize the magnet, means for holding said circuit closer in its normal position, a flexible connection extending to said circuit closer 20 and by means of which it is actuated to close

the circuit and to energize the electro-magnet.

14. In combination with a register having a plurality of banks of counters for registering different classes of fares, of an actuator 25 common to each bank of register counters, setting means for moving said actuator into operative relation with any one of said banks of counters, an electric circuit for moving said actuator and comprising an electro- 30 magnet, a circuit closer controlling said circuit, and means connected with the circuit closer for actuating the same to close the circuit and thus energize the magnet.

In testimony whereof I affix my signature, 35 in presence of two witnesses.

JOHN F. OHMER.
